BENJAMIN F. WININGER, OF LOS ANGELES, CALIFORNIA

TURNSTILE

Application filed March 17, 1930. Serial No. 436,435.

In this specification, and the accompanying drawings I shall describe and show a preferred form of my invention; and specifically mention certain of its more important objects. I do not limit myself to the form disclosed, since various changes and adaptations may be made therein without departing from the essence of my invention as hereinafter claimed; and objects and advantages, other than those specifically mentioned, are included within its scope.

This invention relates to turnstiles, and more especially to turnstiles for use in chain stores and the like.

An object of the invention is to provide an improved head construction for turnstiles in which the rotary part is furnished with novel means for controlling the direction of rotation thereof.

Other objects of the invention are to, in general, simplify and improve upon the construction of turnstiles thereby rendering them more durable, more dependable in operation, and less apt to get out of order.

Other objects, advantages and features of invention may hereinafter appear.

Referring to the accompanying drawings which illustrate what is at present deemed to be a preferred embodiment of the invention,

Fig. 1 is a top plan view of the head portion, parts being removed to disclose underlying construction.

Fig. 2 is a plan view of the head cover.

Fig. 3 is a mid-sectional view of Fig. 1 in direct projection thereof, and also of the remaining central portion of the device.

Fig. 4 is a perspective view of the complete device.

Referring in detail to the drawings, to the top of post 7 is secured a head 8 which, by preference and as shown, consists of a horizontal circular plate 9 having an upstanding peripheral flange 10. Said plate 9 is desirably attached to the post 7 by means of screws 12, and is provided with a central aperture 13 which is disposed axially of said post.

Upon the top of head 8 is loosely mounted a circular cover plate 15 which is of the same diameter as said head 8. Said cover plate 15 has a central aperture 16 which corresponds

in size to the aperture 13 through plate 9 and which is located directly above the latter aperture.

The upstanding flange 10 with which plate 9 is provided, said flange being preferably cast integral therewith, has formed upon its inner face a series of ratchet teeth 20, which, however, are not arranged to receive a pawl for movement in one direction only, but are of equal length and slope on both sides of each tooth, thereby adapting them for controlling the movement of a pawl-carrying member in both directions, as will hereinafter be described.

Within the internally toothed ratchet member provided by the flange 10, is mounted a rotatable bar 21 which is provided with a bore or hole 22. Said bar 21 is secured to the lower side of disc 15 by means of any suitable fastening device such as screw 23. With the bore 22 of said bar brought into alignment with the aforementioned holes 13 and 16, a lag screw 25 is inserted through these aligned openings in order to provide a pivot whereon the plate 15 and bar 21 may rotate.

It will be seen that said bar 21 is shown secured in place solely by means of the single attaching screw 23 in conjunction with the pivot pin 25, said pin extending through the central portion of said bar, and the single attaching means provided by the screw 23 extending through said bar at a different point along its length. Although but a minor feature of the invention, yet this simplified structure is not without its importance.

One end of said bar 21 is provided with a bifurcated portion 27 within which is pivotally supported between its ends an elongated pawl or dog 28 by means of a pivot pin 29.

The actions of said pawl are controlled by means of a tension spring 30, one end of said spring being securable to either end portion of said pawl, and the other end of said spring being securable to either side of said bar. In Fig. 1, said bar 21 is shown provided at each side with a socket 21a which is adapted to receive a removable pin 21b whereby the tension spring 30 may be secured to either side portion of said bar. Each end of said pawl 28 is provided with an aperture 28a to pro-

vide for securing the adjacent end of spring 30 thereto by means of a link or pin 28b. It will thus be seen that said spring is reversible in order to position either end of the pawl for cooperation with the ratchet teeth 20.

5 The turnstile head is preferably provided with four equally spaced radial arms 35, which may be made of wood and which are in that case mortised together at their intersection so as to all lie in the same plane. A 10 central hole 36 is provided through these arms to provide for insertion of the lag screw 25.

Returning again to plate or disc 15 which is loosely seated upon the top of the head or 15 member 8, said plate 15 may be a casting and in any case is provided near its periphery with four equally spaced upstanding lugs 40, each of said lugs having a right angled inwardly 20 projecting corner portion which is adapted to fit between the external angles of the assembled arms 35. A plurality of screws 46 are provided to secure the arms 35 to the upper side of plate 15.

An ornamental member 45 may be secured 25 to the top and central portion of the device by means of pins 46.

Between its bifurcations bar 21 is provided with a curved crotch portion 21c which forms a stop for pawl 28 in whichever of the two 30 positions said pawl may be mounted. This construction limits the action of the spring and also permits the turnstile to be rotated only in the predetermined direction desired.

In assembling the various parts of the device, the base plate 9 of the nonrotatable head 8 is first secured in place on the top of the post 7 with the opening 13 of said plate located axially of said post, the screws 12 being inserted through openings provided therefor in said plate 9 and screwed into the top 40 of the post. Then the bar 21, to which the pawl 28 and spring 30 have previously been attached, is secured to one side of the cover plate 15 by means of the screw 23 in such a manner that the bore 22 through said bar may be brought into alignment with the bore 16 through said plate 15. Then the operating arms 35 which have previously been mortised together at their centers at right angles to 45 each other, are secured to the side of the plate 15 opposite to bar 21 by means of the screws 42, the opening 36 through the central portions of said bars being positioned in alignment with the opening 16 through the plate 50 15. Said arms 35, will of course, be circumferentially adjusted to cause the lugs 40 to fit into the angles between the adjacent arms. Next the opening 16 of plate 15 and bore 22 of bar 21 are brought into alignment with 55 each other and the lag screw 25 is screwed downwardly into the top of the post 7 in the position shown. Lastly the ornamental member 45 may be centrally attached by the pins 46 to the top of the device, as shown.

65 When it is desired to change the position

of pawl 28 and spring 30 from the position shown in full lines in Fig. 1 to the position shown in dotted lines in said view, for the purpose of making the turnstile head rotatable in the opposite direction, the ornamental member 45 is removed, the lag screw 25 is unscrewed from the post 7, and then the cover plate 15 together with the cross arms 35 are removed and the spring 30 is detached from its full line adjustments and is reattached on the opposite side of the bar 15.

Claims:

1. In a turnstile, a rotatable head, and a nonrotatable support upon which said head is mounted, there being a singly pivoted reversible pivotally mounted double acting pawl and ratchet device operating between said head and support to adapt said head to rotate in either a right-hand or left-hand direction as predetermined, and yieldable means for maintaining an engagement of said pawl with said ratchet in either position selected.

2. In a turnstile, a rotatable head, and a stationary support upon which said head is mounted, there being a pivotally mounted double acting pawl and ratchet device acting between said head and support, said device comprising a dog having two tooth-engaging portions at opposite sides of its pivot either of which are adapted to cooperate with the teeth of said ratchet device and a reversible spring adapted to yieldingly maintain either of said tooth-engaging portions in the operative position, as predetermined, to govern the direction in which the turnstile may be rotated.

3. In a turnstile, a stationary support provided with a toothed element; and a rotatable head mounted upon said support, said head being provided with a double acting pawl member which between its ends is pivoted thereto and an interchangeable spring adapted to be attached to said pawl in either of two positions in order to reverse the direction in which the turnstile is rotatable, either end of said pawl being adapted to cooperate with said toothed element.

4. In a turnstile, a stationary support provided with an internally toothed ratchet member; and a rotatable head mounted upon said support, said head carrying a bar adapted to rotate therewith within the toothed portion of said ratchet member, there being a double-acting pawl or dog pivotally connected between its ends to said bar, and a reversible spring to control said pawl, one end of said spring being securable to either end of said pawl and the other end of said spring being securable to said bar at either side thereof, thereby to determine the direction in which the turnstile head may be rotated, either end of said pawl being adapted to cooperate with the teeth of said ratchet mem- 125 ber.

5. A turnstile comprising two main members one of which is rotatable with relation to the other, one of said members being provided with an internally toothed ratchet wheel and the other of said members carrying a bar mounted within said ratchet wheel and extending diametrically thereof, there being pivotally secured to said bar at substantially its mid-width, an elongated double-acting pawl, the end portions of said pawl projecting laterally beyond the sides of said bar, and a detachable spring being secured to either side of said bar and to either end of said pawl to render the connection of said pawl reversible, either end of said pawl being adapted to cooperate with the teeth of said ratchet wheel.

6. A turnstile provided with a support, an internally toothed substantially circular member fixed to said support, a rotatable arm-carrying cover plate loosely mounted upon said toothed member, a bar secured to the under side of said cover plate in diametrical internal relation to said circular member, a pivot pin extending through said bar, plate and circular member, and anchored to said support, attaching means located in said bar at a different point along the length thereof than said pivot pin to secure said bar to said cover plate, and a pawl mounted on said bar to cooperate with the teeth of said circular member.

7. A turnstile provided with a support, an internally toothed substantially circular member fixed to said support, a rotatable arm-carrying cover plate loosely mounted upon said toothed member, a bar secured to the under side of said cover plate in diametrical internal relation to said circular member, said bar having an end portion provided with a bifurcation, and a pawl mounted in said bifurcation and cooperating with the teeth of said circular member.

8. A turnstile provided with a support, an internally toothed substantially circular member fixed to said support, a rotatable arm-carrying cover plate loosely mounted upon said toothed member, a bar secured to the under side of said cover plate in diametrical internal relation to said circular member, said bar having an end portion provided with a bifurcation, and a pawl mounted in said bifurcation and cooperating with the teeth of said circular member, said bar being provided between its bifurcations with a stop shoulder or surface to form a double support to lock said pawl against retrograde movement.
